Primary Examiner — George D. Kirschbaum*Assistant Examiner* — Maria J Edwards(74) *Attorney, Agent, or Firm* — Schwegman, Lundberg & Woessner, P.A.(57) **CLAIM**

The ornamental design for a mobile device case, as shown and described.

DESCRIPTION

FIG. 1 is a top, front-right perspective view of the mobile device case;

FIG. 2 is a bottom, rear-left perspective view thereof;

FIG. 3 is a rear elevation view thereof;

FIG. 4 is a front elevation view thereof;

FIG. 5 is a bottom plan view thereof;

FIG. 6 is a top plan view thereof;

FIG. 7 is a left side elevation view thereof; and,

FIG. 8 is a right side elevation view thereof.

Broken lines in the drawings illustrate portions of the article and form no part of the claimed design.

1 Claim, 5 Drawing Sheets(56)
